UNITED STATES PATENT OFFICE.

JOSEPH N. REYNOLDS, OF ATLANTIC, IOWA.

DESIGN FOR A GLOVE.

54,333.

Specification for Design.

Patented Dec. 23, 1919.

Application filed July 25, 1919. Serial No. 313,385. Term of patent 7 years.

To all whom it may concern:

Be it known that I, JOSEPH N. REYNOLDS, a citizen of the United States of America, residing at Atlantic, in the county of Cass and State of Iowa, have invented a new, original, and ornamental Design for a Glove, of which the following is a specification, reference being had to the accompanying drawing, forming part thereof.

The figure is a plan view of a glove showing my new design.

I claim:

The ornamental design for a glove, as shown.

JOSEPH N. REYNOLDS. [L.S.]
